UNITED STATES PATENT OFFICE.

BURNHAM C. STICKNEY, OF ELIZABETH, NEW JERSEY, ASSIGNOR TO UNION TYPEWRITER COMPANY, OF JERSEY CITY, NEW JERSEY, A CORPORATION OF NEW JERSEY.

TYPE-WRITING MACHINE.

No. 816,380.

Specification of Letters Patent.

Patented Jan. 16, 1906.

Application filed April 8, 1903. Serial No. 151,336.

To all whom it may concern:

Be it known that I, BURNHAM C. STICKNEY, a citizen of the United States, and a resident of Elizabeth, in the county of Union and State of New Jersey, have invented certain new and useful Improvements in Type-Writing Machines, of which the following is a specification.

This invention relates to type-writing machines, particularly those of the front-strike class; and its object is to improve the key touch and to simplify and improve the type-actions.

My invention consists in certain features of construction and combinations of devices, which will be hereinafter fully set forth, and particularly pointed out in the concluding claims.

In the drawings forming part of this specification, Figure 1 is a central longitudinal vertical section of a front-strike writing-machine made in accordance with my improvements, the parts of the type-action being illustrated in normal position. Fig. 2 shows the positions assumed by the parts at the time that the type impression is made. Fig. 3 is a cross-section of the machine, taken at about the line x x of Fig. 1. Fig. 4 is a diagram illustrating the convergence of the rear portions of the key-levers.

In the several views like signs denote like parts.

The framing of the machine may comprise a base 1, corner-posts 2, and a top plate 3. A carriage having a platen 4 may travel over the top plate. Types 5 are mounted upon the ends of rearwardly-striking type-bars 6, which are pivoted upon a curved rod 7 and work in radial slots 8, cut in a segment 9, in which said curved rod is fixed. The segment may be mounted by ears 10 upon a pair of fixed vertical guide-posts 11, whereby the segment may be shifted vertically. The type-bars at their forward ends may rest upon a pad 12, supported upon the forward ends of rods 13, secured upon the type-bar segment.

In rear of the type-bars is mounted a system of upstanding sublevers of the first order, consisting of upwardly-extending arms 14 and downwardly-extending arms 15, the latter being preferably shorter than the former. These sublevers are mounted upon a

straight transverse fulcrum-rod 16, which is carried upon a bar 17, the latter having vertical slots 18 for the sublevers and being fixed upon lugs 19 at opposite sides of the machine-base. At their upper ends the sublevers are connected by forwardly-extending links 20 directly to the type-bars.

A system of T-shaped key-levers is provided comprising arms 21, which extend forwardly beneath the type-bars and carrying keys 22, upwardly-extending arms 23, which are pivoted at 24 directly to the pendent arms 15 of the upstanding sublevers, and downwardly and forwardly inclined arms 25, which are preferably longer than the arms 23 and have elongated convexly-curved treads 26, whereby the arms are adapted to have a rocker motion upon a downwardly and forwardly inclined and concave-faced bar, fulcrum-plate, or support 27, which is arranged on edge and is supported at its ends upon the side walls of the base. Upon said bar is provided a guide-comb 28 for the arms 25. The rear end of the key-lever is wholly supported by the pendent arm of the sublever, so as to prevent the elongated tread from becoming displaced vertically or longitudinally from operative position. When a key is depressed, a tendency is produced upon the part of the entire key-lever to vibrate about the pivotal point 24. Hence the arm 25 presses rearwardly against the support, but rocks down therealong, said support serving as a fulcrum for the lever. During this movement the pivotal point 24 is swung forwardly with the pendent arm 25 of the sublever, as at Fig. 2. By the movement of the upper arm 14 of the upstanding lever the link 20 is drawn rearwardly and the type-bar is swung up to print. Upon the release of the key from pressure the parts may be returned by means of any suitable spring, that herein illustrated being in the form of a diagonal draw-spring 29, caught at one end upon a prolongation 30 of the link 20 past the point of connection with the lever-arm 14 and caught at the other end in said arm 14. During the printing movement of the type-action said spring is expanded, and its contraction serves to return the parts to normal position. By reason of the rocker movement of the arm upon the plate or support the leverage or purchase of the key upon the type-bar, which

100
105

leverage is so great at the initial part of the stroke as to avoid jarring to the finger of the operator, gradually decreases until the stroke is completed, the effect being to soften the 5 key touch and also to increase the speed of the type as it approaches the platen, so that it is caused to deliver a powerful blow upon the paper placed thereon. At Fig. 2 it will be seen that the key-lever is equivalent to a 10 simple bell-crank or elbow lever, the power being applied to the key, the fulcrum being at the point of contact of the lower end of the rocker with the support or plate and the load-point being at 24, these three points being at 15 the apexes of a triangle. It will be noted at said figure that when the parts are in the position shown—that is, at the completion of the stroke—the leverage of the key upon the type-bar is the least.

20 Referring to Fig. 3, it will be noted that the type-bars lie in an arc and that the horizontal links 20 are correspondingly disposed at progressively-increasing heights at the sides of the machine. The upper arms 14 of the sub- 25 levers are made accordingly shortest in the middle of the system and of progressively-increasing length from the middle to the sides of the system. The short arms 15 of said levers increase in length in like manner. The 30 upwardly-extending cross-arms 23 of the key-levers are longest in the middle and progressively shorter from the middle to the sides of the system, thereby accommodating the increase in the length of the arms 15, to 5 which they are pivoted. The parts may be proportioned so that a substantially uniform leverage for all of the keys upon the type-bars is preserved, so as to give the keys a substantially uniform dip. The system of links is of substantially the same width as the system of type-bars and the upstanding levers, while the system of key-levers converges at its rear portion to equal the width of the system of upstanding levers.

45 Variations may be resorted to within the scope of my invention, and portions of my improvements may be used without others.

Certain features herein shown are described and claimed in my pending application filed April 6, 1903, Serial No. 151,384.

What I claim as new, and desire to secure by Letters Patent, is—

1. In a type-writing machine, the combination of a series of type-bars, a series of 55 sublevers connected thereto, a series of key-bearing forwardly-extending levers pivoted at their rear ends to said sublevers, angular arms on the rear ends of said key-bearing levers, said angular arms being provided with 60 elongated treads, and a support upon which said treads have a rocker motion in an up and down direction.

2. In a type-writing machine, the combination of a series of rearwardly-striking type- 65 bars, a series of upstanding sublevers connect-

ed thereto, a series of key-bearing forwardly-extending levers pivoted at their rear ends to said upstanding levers, angular arms on the rear ends of said key-levers, said angular arms being provided with elongated treads, and a support upon which said treads have a rocker motion.

3. In a front-strike writing-machine, the combination of a series of rearwardly-striking type-bars, a series of key-bearing levers 75 extending forwardly beneath the type-bars, upwardly-extending arms on said key-levers, downwardly-extending arms on said key-levers, a set of sublevers connected to one set of said arms and also connected to the type-bars, elongated treads on the other set of said arms, and a support along which said treads have a rocker motion.

4. In a front-strike writing-machine, the combination of a series of rearwardly-striking type-bars, a series of key-bearing levers 85 extending forwardly and each having ramifications at its rear end, a set of sublevers connected to one set of ramifications and also connected to the type-bars, elongated treads 90 formed on the other set of ramifications, and a support upon which said treads have a rocker motion.

5. In a front-strike writing-machine, the combination of a series of rearwardly-striking type-bars, a series of upstanding levers in 95 rear of the type-bars, a series of key-operated levers each having ramifications at their rear ends, one set of ramifications being pivoted directly to the lower ends of said upstanding levers, and the other set of ramifications having elongated treads, and bearings along which said treads have a rocker motion.

6. In a front-strike writing-machine, the combination of a series of rearwardly-striking type-bars, a series of upstanding levers of the first order mounted in rear of said type-bars, links connecting said levers to said type-bars, T-shaped levers including forwardly-extending key-bearing arms, upwardly-extending arms which are pivoted directly to the lower arms of said upstanding levers, and downwardly-extending arms having elongated treads; and a support upon which said treads have a rocker motion.

7. In a front-strike writing-machine, the combination of a series of rearwardly-striking type-bars, a series of upstanding levers of the first order connected to said type-bars, and forwardly-extending key-levers pivoted 120 to the lower arms and below the fulcrums of said upstanding levers; said key-levers having elongated treads; and a fixed support along which said treads have a rocker motion.

8. In a front-strike writing-machine, the combination of a series of rearwardly-striking type-bars, a series of upstanding sublevers in rear of said type-bars, each of said levers being fulcrumed between its ends, links 125 130

connecting the upper ends of said levers to said type-bars, forwardly-extending T-shaped key-levers pivoted at one set of their cross-arms to the depending arms of said upstanding sublevers, elongated treads formed upon the other set of cross-arms, and means for supporting and guiding said treads during the movements of said key-levers.

9. In a front-strike writing-machine, the combination of a series of rearwardly-striking type-bars, a series of T-shaped key-levers, keys upon one set of arms of said key-levers, elongated treads upon another set of arms of said key-levers, a support along which said fulcrums have a rocker motion, and connections between the third set of arms of said key-levers and said type-bars; said connections including a set of sublevers.

10. In a front-strike writing-machine, the combination of a series of rearwardly-striking type-bars, a series of T-shaped key-levers, keys upon one set of arms of said key-levers, elongated treads upon another set of arms of said key-levers, a support along which said fulcrums have a rocker motion, and connections between the third set of arms of said key-levers and said type-bars; said connections including both a set of sublevers to which the last-mentioned key-lever arms are directly pivoted, and links extending from said sublevers to the type-bars.

11. In a front-strike writing-machine, the combination of a series of rearwardly-striking type-bars, a series of upstanding levers of the first order mounted in rear of said type-bars, links connecting said levers to said type-bars, T-shaped levers including forwardly-extending key-bearing arms, upwardly-extending arms which are pivoted directly to the lower arms of said upstanding levers, and downwardly-extending arms having elongated treads, and a support upon which said treads may have a rocker motion, said system of upstanding levers being less in width than said system of key-levers at the keyboard, and said system of key-levers converging rearwardly.

12. In a front-strike writing-machine, the combination of a series of rearwardly-striking type-bars, a series of upstanding levers of the first order mounted in rear of said type-bars, links connecting said levers to said type-bars, T-shaped levers including forwardly-extending key-bearing arms, upwardly-extending arms which are pivoted directly to the lower arms of said upstanding levers, and downwardly-extending arms having elongated treads; a support upon which said treads have a rocker motion; and a single transverse fulcrum-rod upon which said upstanding levers are pivoted; the upwardly-extending arms of said sublevers being shortest at the middle of the system and of progressively-increasing length from the middle to the sides of the system, and their down-

wardly-extending arms being of correspondingly-increasing lengths.

13. In a front-strike writing-machine, the combination of a series of rearwardly-striking type-bars, a series of upstanding levers of the first order mounted in rear of said type-bars, links connecting said levers to said type-bars, T-shaped levers including forwardly-extending key-bearing arms, upwardly-extending arms which are pivoted directly to the lower arms of said upstanding levers, and downwardly-extending arms having elongated treads; a support upon which said treads may have a rocker motion; and a single transverse fulcrum-rod upon which said upstanding levers are pivoted; the upwardly-extending arms of said sublevers being shortest at the middle of the system and of progressively-increasing length from the middle to the sides of the system, and their down-

wardly-extending arms being of correspondingly-increasing lengths, and the upwardly-extending arms on the key-levers being longest at the middle of the system and progressively decreasing in length from the middle to the sides of the system.

14. In a front-strike writing-machine, the combination of a series of rearwardly-striking type-bars, a series of sublevers connected to the type-bars, and a series of key-bearing levers pivoted to the sublevers; one of said sets of levers having arms provided with elongated treads, the said sublevers vibrating on fixed pivots arranged above the key-levers; and a fixed support upon which said treads have a rocker motion during the type-bar movements.

15. In a type-writing machine, the combination with a series of rearwardly-striking type-bars, of a series of upstanding levers of the first order connected to said type-bars; said levers being fulcrumed in a transverse horizontal line, their upwardly-extending arms being shortest in the middle of the system and progressively increasing in length from the middle to the sides of the system, and their downwardly-extending arms being of correspondingly-increasing lengths but shorter than the upwardly-extending arms; a system of key-levers connected to said upstanding levers and having elongated treads; and a support upon which said treads have a rocker motion.

16. In a front-strike writing-machine, the combination of a series of rearwardly-striking type-bars, a series of upstanding levers of the first order mounted in rear of said type-bars, links connecting said levers to said type-bars, T-shaped levers including forwardly-extending key-bearing arms, upwardly-extending arms which are pivoted directly to the lower arms of said upstanding levers, and downwardly-extending arms having elongated treads; a support upon which said treads have a rocker motion; and a sys-

tem of returning-springs connected to said upstanding levers.

17. In a type-writing machine, the combination of a series of types, a series of type-operating arms, a series of T-shaped levers pivoted at one set of their cross-arms to said type-operating arms, elongated treads formed upon the other set of said cross-arms, a fixed support having an elongated transverse tread along which said treads on the levers have a rocker motion to effect an automatic change of leverage, and a series of keys carried by the stem-like arms of the T-shaped levers.

18. In a type-writing machine, the combination of a series of type-bars, a series of key-bearing T-shaped levers, a series of sublevers to which said key-levers are pivoted at one set of their cross-arms, elongated treads formed upon another set of the arms of said T-levers, a support along which said treads may have a rocker motion, and a set of returning-springs.

19. In a type-writing machine, the combination of a series of type-bars, a series of key-bearing T-shaped levers, a series of sublevers to which said key-bearing levers are pivoted at one set of their cross-arms, elongated treads formed upon the other set of cross-arms of said T-levers, and a support along which said treads have a rocker motion; said treads being materially longer than the cross-arms that are pivoted to the sublevers.

20. In a type-writing machine, the combination of a series of type-bars, a series of keys, and two sets of levers between said keys and said type-bars; one set of said levers being pivoted to the other, and one set of said levers consisting of bell-crank arms which carry said keys, and having arms provided with elongated treads; and a fixed support upon which said treads have a rocker motion.

21. In a type-writing machine, the combination of a series of type-bars and a series of key-bearing bell-crank arms connected thereto; the fulcrum-arms of said bell-crank arms having elongated treads; and arms upon which said fulcrum-arms are pivoted and whereby they are supported against endwise displacement; and a support along which said treads have a rocker motion.

22. In a type-writing machine, the combination of a series of type-bars; a series of T-shaped levers comprising forwardly-extending key-bearing arms, upwardly-extending arms, and downwardly-extending arms having elongated treads; a support along which said treads have a rocker motion; and a series of sublevers between said upwardly-extending arms and said type-bars.

23. In a type-writing machine, the combination of a type-bar and a key-operated lever connected thereto; said lever having an elongated curved tread portion; and a support along which said tread has a rocker motion;

said support being curved in the direction of the length of said tread.

24. In a type-writing machine, the combination of a type-bar and key-operated lever connected thereto; said lever having an elongated curved tread portion; and a support along which said tread has a rocker motion; said support being curved in the direction of the length of said tread, the curve of the support nearly matching but having a different radius from the curve of the tread.

25. In a type-writing machine, the combination of a type-bar and a key-operated lever connected thereto; said lever having an elongated curved tread portion; and a support along which said tread has a rocker motion; said support being curved in the direction of the length of said tread, the tread curve being convex, and the support curve being concave and of greater radius than the tread curve.

26. In a type-writing machine, the combination with a type-bar of a key-lever connected thereto and having a downwardly and forwardly inclined angle-arm, which is provided with an elongated tread; and a downwardly and forwardly inclined support along which said tread has a rocker motion; at least one of said tread and support elements being curved.

27. In a type-writing machine, the combination with a type-bar of a key-lever connected thereto and having a downwardly and forwardly inclined arm which is provided with an elongated convexly-curved tread; and a downwardly and forwardly inclined support along which said tread has a rocker motion.

28. In a type-writing machine, the combination with a type-bar and a key-lever connected thereto and having a downwardly and forwardly inclined arm which is provided with an elongated convexly-curved tread; and a downwardly and forwardly inclined concave support along which said tread has a rocker motion; the curve of the support having greater radius than the curve of the tread.

29. In a type-writing machine, the combination of an upright elongated fulcrum, a member with an upright elongated tread that has a rocking movement on said fulcrum, a key connected to said member, and a type-bar operatively connected to said member.

30. In a type-writing machine, the combination of an upright elongated fulcrum, a key-lever with an upright elongated tread that has a rocking movement on said fulcrum, a sublever actuated by said key-lever, and a type-bar operatively connected to said sublever.

31. In a type-writing machine, the combination of a series of type-bars and a series of key-operated bell-crank arms connected thereto and having fulcrum-arms; the fulcrum-arms of said bell-crank arms having elongated treads; and a fulcrum-plate whereon said treads have a rocker motion.

32. In a type-writing machine, the combination of a series of type-bars and a series of key-bearing bell-cranks connected thereto and having fulcrum-arms; the fulcrum-arms of said bell-cranks having elongated treads; and a fulcrum-plate whereon said treads have a rocker motion.

33. In a front-strike writing-machine, the combination of a series of rearwardly-striking type-bars; a series of bell-cranks comprising forwardly-extending key-bearing arms and angular arms, the latter being connected to said type-bars; the points of connection of said angular arms to said type-bars moving forwardly and rearwardly, and said bell-cranks having elongated treads; and a fulcrum-plate along which said treads have a rocker motion.

34. The combination with a type-bar of a three-arm lever, one arm of said lever bearing a key, another arm thereof being connected to said type-bar, and a third arm thereof having an elongated tread; and a bearing member along which said tread has a rocker motion and a change of fulcrum during the rocking motion.

35. In a front-strike writing-machine, the combination of a series of rearwardly-striking type-bars; a series of key-bearing levers extending forwardly beneath the type-bars, upwardly-extending arms on said key-levers, downwardly-extending arms also on said key-levers, connections between one set of said arms and said type-bars, elongated treads on the other set of said arms, and a support along which said treads have a rocker motion.

36. In a type-writing machine, the combination of a series of type-bars and a series of key-operated bell-cranks connected thereto; the fulcrum-arms of said bell-cranks having

elongated treads; a fulcrum-plate whereon said treads have a rocker motion; and means for preventing said treads from becoming displaced longitudinally.

37. In a type-writing machine, the combination of a series of type-bars; a series of key-bearing bell-cranks connected thereto; the fulcrum-arms of said bell-cranks having elongated treads, a fulcrum-plate whereon said treads have a rocker motion, said fulcrum-plate being arranged on edge, and means for preventing longitudinal displacement of said treads.

38. In a front-strike writing-machine, the combination of a series of rearwardly-striking type-bars; a series of T-shaped levers comprising forwardly-extending key-bearing arms, upwardly-extending arms connected to said type-bars, and downwardly-extending arms having elongated treads; means for preventing vertical displacement of said downwardly-extending arms; and a fixed fulcrum-plate upon which the latter arms have a rocker motion.

39. The combination with a type-bar, of a T-shaped key-lever; connections between said type-bar and one arm of said key-lever, said connections comprising a link, a key carried by another arm of said lever, and a bearing for the third arm of said lever which affords a change of fulcrum during the depression of the key-lever.

Signed in the borough of Manhattan, city of New York, in the county of New York and State of New York, this 4th day of April, A. D. 1903.

BURNHAM C. STICKNEY.
